UNITED STATES PATENT OFFICE.

IRWIN H. HALFERTY, OF PITTSBURGH, PENNSYLVANIA

SMOKING PIPE OR TUBE

Application filed June 4, 1924. Serial No. 717,689.

This invention is for a smoking pipe, or smoking tube.

5 It is generally recognized that tobacco smoking is more enjoyable if the smoke can be cooled to an appreciable extent, before it reaches the mouth, and this is particularly true in connection with pipes. In order to effect cooling of the smoke, pipes with extremely long stems are made. Other forms
10 of pipes have been devised wherein the smoke passage extends back and forth inside the pipe stem. As heretofore made, however, the back and forth passages have all been so arranged that efficient cooling is not
15 obtained, the various passages generally being in a solid block of material, so that all are heated to substantially the same degree by conduction, and with very little extra radiating surface really being provided.
20 The present invention has for its principal object to provide a smoke tube, in either a pipe stem or cigar or cigarette tube or holder, a novel conduit for the smoke which may provide, in a pipe or holder of ordinary
25 length, a smoke passage equal to several times the length of the stem with substantially the entire length of said conduit exposed, and out of contact with adjacent portions of the conduit, whereby a large radiating surface
30 and effective cooling may be obtained.

A further object of the invention is to provide a simple way of constructing this smoke conduit and permit of its being cleaned.

35 A further object of the invention is to provide a convertible pipe, cigar, and cigarette holder of novel construction.

These and other objects and advantages are attained by my invention, which may be understood by reference to the accompanying drawings, in which:—

Fig. 1 is a side view, partly in section, of a pipe embodying the invention.

Fig. 2 is a transverse section in the plane of line II-II of Fig. 1.

45 Fig. 3 is a similar section in the plane of line III-III of Fig. 1.

Fig. 4 is a very much enlarged view of one of the bends in the smoke conduit, showing the snap cover for the cleaning opening therein.

Fig. 5 is a transverse section in the plane of line V—V of Fig. 4.

Fig. 6 is a view similar to Fig. 1 showing a convertible pipe, cigar and cigarette holder, embodying my invention.

Fig. 7 is a side view of a further modification of the invention.

Fig. 8 is a top view of the bowl of the form shown in Fig. 7.

Fig. 9 is a detail view of a smoke discharge nozzle that may be used in connection with the pipe. 60

Referring first to the construction shown in Figs. 1 to 5, inclusive, of the drawings, 5 designates the bowl of a pipe having a hollow stock 6 and a detachable mouthpiece 7. Leading out from the bowl of the pipe, is a removable tube, preferably of aluminum, similar to that now commonly used in pipes, but considerably longer. This tube, designed generally as 8, is bent back and forth upon itself several times, with each length out of contact with the others, several lengths thus being provided. I prefer to have five such lengths, as this number fits well into a fair sized stock. The length leading from the bowl is designated 9, and the central length leading into the stem, into which its end is slidably fitted, is designated 10. The intervening lengths are designated 11. 70 75 80 85

As before stated, each length is preferably out of contact with the other lengths, and preferably, but not necessarily, out of contact with the interior of the stock. The entire tube may be removed upon removal of the mouth piece 7. 85

The outside wall of each curve in the tube or conduit, is cut away, as indicated by the dotted line in Fig. 4, and as shown in Fig. 5, 90 so that the entire curve may be accessible for cleaning, and a straight, flexible pipe cleaner of the usual type inserted at one end of a length 9, 10 or 11 and projected from the other end. 95

A suitable cap, however, is provided for each opening to make it substantially air tight in use. A form of such cap is shown in Figs. 5 and 6. The cap 12 is of suitable shape to conform to the curvature of the 100 tube, and may have integral prongs 13 thereon oppositely disposed with respect to each other and slightly curved to embrace the tubing. The inherent resilience of the prongs holds the cap tightly, but releasably 105 on the conduit. In order to prevent them from being lost, each cap may have a hinge 14 at one end thereof, through which a wire or clip 15, extending around the conduit, passes to pivotally retain the cap in place. 110

Each cap may have a cork sealer or gasket 16 on its inner face, to insure a tight joint.

A removable cap of this kind provides a simple and efficient closure that enables the tube to be easily cleaned when necessary. This is a highly desirable feature, because, due to the greater condensation in the cool smoke, more liquid will accumulate in the pipe.

19 Because it is desirable to have as little moisture collect in the pipe as possible, I may fit the hollow shank 17 of a hollow, finely perforated button 18, best shown in Fig. 9, into the mouthpiece. This will tend 15 to prevent much of the saliva from the mouth from entering the pipe, whereas a single large opening, as generally provided, will not.

In the form of the invention shown in 20 Fig. 6, the bowl 20 of the pipe does not have the usual integral stock, but is provided with a short extension 21 to which the jointed stem hereinafter described attaches.

This stem comprises a tubular body 22 25 and a separable mouthpiece 23, between which may be a heat insulating connector 24. The body 22 has a socket 25 in its forward end and a chamber 26 in the main portion of its length. The socket 25 is shaped 30 to receive the end of a cigar, so that, by detaching the bowl, the stem may be used as a cigar holder.

This socket is supplied with a removable plug 27 that has a recess 28 therein of such 35 shape and size that it may receive the end of a cigarette. Thus, the article is a convertible pipe, cigar holder and cigarette holder.

In the chamber 26 is a tube or conduit 29 40 in all respects similar to tube 8 described in connection with Fig. 1. The metal tube can be readily removed for cleaning.

In both forms of the invention already described, suitable openings are provided in 45 that portion of the stock or body of the stem to allow for the free circulation of air around the metal tube. Small openings for this purpose are indicated at 30 in both figures and a single large opening at 31 in each figure.

50 In Figs. 7 and 8, the bowl 32 of the pipe is joined to the stem 33 which has a hollow interior. The end of the stem projects into the body of the pipe, the stem having a slot 34 in each side, the slots beginning at the 55 end which joins onto the pipe and extending a short distance along the stem.

A metal smoke tube 35 extends from the bowl along the interior of the hollow part of the stem, and then turns back on itself. 60 The return length emerges from the stem through one of the slots 34 and the tube then extends up and down around the bowl, as indicated at 36, finally re-entering the stem through the other slot and extending 65 therealong to the free end of the mouth-

piece. At each bend or curve is a closure 37 which may be similar to that shown in Fig. 4, so as to give access to all the straight-away lengths for cleaning.

In order that the cooling may be more 70 effective in the form of device illustrated in Figs. 7 and 8, the interior of the pipe may have a central liner 38 of wood or other suitable substance, outside of which is a wall 39 of suitable heat insulating material. This 75 arrangement serves to keep the bowl with which the tube contacts cooler than it otherwise would be. If desired, the bowl could be formed of metal with the liner 38 of wood.

The slotted construction of the stem 33 80 enables the stem to be removed to give access to the smoke tube.

While I have described the invention as being particularly applicable to pipes, it will be readily appreciated that it is equally applicable to other smoking appliances, as 85 cigar and cigarette holders. It will be further understood that the term "pipe" as hereinafter used in the claims shall be construed to cover cigar and cigarette holders. 90

Various changes and modifications other than those illustrated may be made within the contemplation of my invention, and under the scope of the appended claims. 95

I claim as my invention:

1. A tobacco smoking appliance comprising a body member having a tobacco receiving recess at its forward end, a mouthpiece, and a removable metal tube, the said tube bent back and forth upon itself coaxially 100 of the stem and having one end terminating in the tobacco receiving recess and having its other end in communication with the mouthpiece.

2. A tobacco smoking appliance comprising a stem having the body portion thereof hollow, a mouthpiece on one end of the stem, a tobacco receiving means at the other end of the stem, and a tube carried by the stem and extending back and forth along the stem 110 with adjacent lengths thereof separated, one end of the tube communicating with the tobacco receiving means and the other end communicating with the mouthpiece.

3. A tobacco smoking appliance comprising a stem having the body portion thereof hollow, a mouthpiece on one end of the stem, a tobacco receiving means at the other end of the stem, and a tube carried by the stem and extending back and forth along the stem 115 inside thereof with adjacent lengths thereof separated, one end of the tube communicating with the tobacco receiving means and the other end communicating with the mouthpiece, said stem having openings therein to permit of the circulation of air about the tube.

4. A tobacco smoking appliance comprising a stem having a hollow body portion, a mouthpiece at one end, a tobacco receiving 130

means at the other end of the stem, and a metal smoke tube in the hollow interior of the body curved back and forth upon itself and providing a plurality of straight passages, the tube having openings in the curved portions through which a cleaner may be inserted into the straight portions of the tube, and a movable closure for each opening.

10 5. A pipe having a bowl, a stem and a mouthpiece, and a smoke tube leading from the bowl to the mouthpiece, said tube being longer than the entire pipe and being bent back and forth into a plurality of short straight lengths, the bends having an opening therein, and a movable closure for each opening.

6. A pipe having a bowl, a stem and a mouthpiece, and a smoke tube leading from the bowl to the mouthpiece, said tube being longer than the entire pipe and being bent back and forth into a plurality of short straight lengths, each straight length being out of contact with the adjacent lengths, the bends having an opening therein, and a movable closure for each opening.

20 7. A pipe having a bowl, a stem, and a mouthpiece, and a metal smoke tube inside

the stem of greater length than the overall length of the pipe and leading from the bowl to the mouthpiece, the tube being bent back and forth upon itself into a plurality of short straight sections, the bent portions of the tube being open, and removable closures for the openings.

30 8. A pipe having a bowl, a stem, and a mouthpiece, and a metal tube inside the stem through which smoke passes from the bowl to the mouthpiece, said tube being longer than the overall length of the pipe and being curved back and forth into a plurality of short lengths, each length being out of contact with the others, and means at each curve providing access of a cleaner for each length.

40 9. A pipe having a bowl, a stem, a mouthpiece, a smoke tube leading from the bowl to the mouthpiece, said tube being considerably longer than the overall length of the pipe, and having a portion of its length contained in the stem and extending back and forth therein, the remainder of the tube surrounding the exterior of the bowl.

45 In testimony whereof I affix my signature.

IRWIN H. HALFERTY.
